DESIGN FOR A PAGELESS MEMO-PAD HOLDER

Harold R. King, Girard, Ohio

Application April 5, 1944, Serial No. 113,155

Term of patent 14 years

(Cl. D74—1)

To all whom it may concern:

Be it known that I, Harold R. King, a citizen of the United States, residing at R. D. #1 Girard, in the county of Trumbull and State of Ohio, have invented a new, original, and ornamental Design for Pageless Memo-Pad Holder, of which the following is a specification, reference being had to the accompanying drawing, forming part thereof. The figure is a front perspective view of a pageless memo-pad holder showing my new design, the opposite side and the rear being plain.

I claim:

The ornamental design for a pageless memo-pad holder, as shown and described.

HAROLD R. KING.
